CLAIM

The ornamental design for a pair of stabilizers for small boat, as shown and described.

DESCRIPTION

FIG. 1 is a perspective view of a pair of stabilizers for small boat, showing my new design, the stabilizers being in elevated position;

FIG. 2 is an enlarged front elevation view of one of the pair of stabilizers shown in FIG. 1 in lowered position; FIG. 3 is a rear elevation view of FIG. 2 in elevated position;

FIG. 4 is a front elevation view of FIG. 3;

FIG. 5 is a side elevation view of FIG. 4, the opposite side being a mirror image of that shown;

FIG. 6 is a top plan view of FIG. 4;

FIG. 7 is a bottom plan view of FIG. 4; and

FIG. 8 is an enlarged fragmentary sectional view taken along line 8—8 in FIG. 4.

The stabilizer opposite to that shown in FIGS. 2 thru 8 is understood to be a mirror image thereof.

The broken lines in the figures are included only to illustrate the environment, namely, a small boat, and form no part of the design.
